UNITED STATES PATENT OFFICE

JOHN M. CRAIGO, OF HARTFORD, CONNECTICUT

DENTAL MACHINE

Application filed May 23, 1928. Serial No. 280,005.

This invention relates to a machine for use in dental work, and has particular reference to an apparatus for forming wire clasps removably attached to a tooth, and to which a clasp a denture is to be secured.

Heretofore it has been the general practice to make clasps of this sort by hand, a procedure which made the clasps relatively expensive. Considerable difficulty was experienced in properly forming the clasps and the operation was a laborious one and required considerable skill and time on the part of the operator.

The object of the present invention is to provide a simple and effective apparatus by means of which clasps may be accurately formed at a relatively slight expense of time and labor.

By the use of the present machine, clasps varying in size and shape may be quickly and properly formed.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawings, wherein I have shown for illustrative purposes one embodiment which the present invention may take:

Figure 1 is a side elevational view of the machine;

Fig. 2 is a side elevational view of the die elements;

Fig. 3 is a transverse sectional view taken substantially on line 3-3 of Fig. 5;

Fig. 4 is a vertical sectional view taken substantially on line 4-4 of Fig. 3;

Fig. 5 is a front elevational view of the entire machine;

Fig. 6 is a top plan view of the bottom die and the side dies;

Fig. 7 is a view looking at the lower end of the reciprocating male die; and

Fig. 8 is a perspective view of a clasp of

the type adapted to be formed in the machine of the present invention.

In order that the construction and operation of the machine in the application here selected for illustration may be more clearly understood as the description proceeds, the clasp, shown in Fig. 8, will first be described. It is understood, of course, that a clasp of this sort has been and is in general use. This clasp is formed of wire and has a pair of arms ⁵⁵ *a* connected by a U-shaped portion having upright legs *b* and a cross piece *c*. The legs *a* are adapted to straddle a tooth in the mouth and a denture is adapted to be soldered or otherwise secured to the U-shaped portion. ⁶⁰ Obviously, the size and shape of the clasp will vary in accordance with the tooth to which it is to be removably secured and to the denture adapted to be secured to the clasp. ⁶⁵

Referring to the machine in detail, it has a frame with a base 10, a standard 11 and a head 12. Mounted for vertical reciprocating movement in the head is a plunger 13 of any desired construction. This plunger may be moved up and down through any preferred form of mechanism. For example, there may be pivoted in the head a lever 14 the forward end of which is bifurcated so as to straddle a pin 15 carried by the plunger. ⁷⁰ 16 is an operating handle pivoted in the head 12 and having its forward edge bifurcated so as to straddle a pin 17 on the rear end of the lever 14. ⁷⁵

The numeral 20 designates a male die which is in the form of a strip having a groove 21 in its lower end. The side edges of the male die at their lower ends are also grooved, as at 22, so that the grooves 21 and 22 form, so to speak, a U-shaped groove. ⁸⁰

The groove 21 may be vertically arched or bowed as shown in Fig. 4 and also may be transversely curved, as shown in Fig. 7, so as to give the desired shape to the cross piece *c* of the clasp. The male die 20 is adapted to be removably secured to a holder 23 which in turn is removably secured to the lower end of the plunger 13. The upper end of the male die 20 fits in a groove in the holder 23 and may be secured in place by a set screw ⁹⁰ 24. The holder 23 has a stem 25 fitting ⁹⁵ *90* *100*

in a bore in the lower end of the plunger 13. The stem is secured in place by a set screw 26. The inner end of this set screw is tapered or conical, and fits in a correspondingly shaped recess in the stem 25 so as to properly locate the holder and the male die carried thereby with respect to the female die.

The female die is formed of a plurality of die elements which are relatively adjustable so that clasps of various sizes and shapes may be formed by the use thereof. These die elements are so associated as to form a general U-shaped groove which is complementary to the die grooves of the male die 20. The female die includes a central or bottom die element 30 and two side die elements which straddle the bottom die element 30 and extend thereabove. The bottom die element is in the form of a circular post having in its upper end a transverse groove 31 shaped correspondingly to and opposed to the groove 21 in the bottom edge of the male die 20. In the present illustrative disclosure, each of the side die elements is in the form of a pair of blocks 32, the adjacent inner corners of which are concavely rounded so as to form a semi-circular groove 33 which is complementary to the opposed side groove 22 of the male member.

The pairs of die blocks 32 are respectively carried by holders 35 mounted for vertical and transverse adjustments.

The numeral 40 designates a transversely extending guide rail which is preferably removably secured to the base 10 beneath the plunger 13 in order that this rail, together with the parts carried thereby, may be removed when the frame is to be used in connection with other devices. Extending through and pinned to the rail is a stud 41, the lower end of which fits in an opening in the base 10 and is secured in place by a set screw 42. The bottom die element 30 is removably secured to the upper end of the stud 41 by means of a set screw 44. The set screw 44 is formed similarly to the set screws 26 and 42 so as to properly position the die element 30 and prevent it from turning. Adjustably mounted to each side of the stud 41 is a slide 45. These slides are adapted to be locked in adjusted position on the rail 40 by clamping screws 46. Carried by each slide 45 is a vertical post 47, which is screw-threaded as at 48, and the upper end of which is smooth and flattened at one side, as at 49. Each of the screw-threaded portions 48 receives an adjusting nut 50. The holders 45 have vertical round openings 55 which respectively receive the posts 47. By preference, each of the posts has a pin 56 and each opening 55 has a vertical groove 57 adapted to receive the pin. These holders are adapted to rest upon the adjusting nuts 50 and are secured in adjusted position by set screws 58. The opposed faces of the supports or holders 35 are recessed so as to receive the die blocks 32, these die blocks

being secured in place by screws 60 (see Fig. 3).

Upon the upper ends of the side die elements are forming or bending surfaces, about which the arms *a* are adapted to be shaped. Each of the side die elements is provided with a pair of upwardly extending projections 70 and 71. The outside surfaces 72 of the projections 70 are curved or rounded so that the two surfaces 72 form the opposite parts of a circle, so to speak. The outside surfaces 73 of the projections 71 are curved in a similar manner. Between each pair of projections 70 and 71 is a slot 74 which is in alignment with a respective die groove 33. The projections 71 are smaller than the projections 70. When a clasp of large size is to be made, the members 70 can be employed, and when a clasp of smaller size is to be made the projections 71 can be used. At the top of each die block 32 and at the base of the curved surfaces 72 and 73 are vertically curved or arched bending or forming surfaces. For example, at the base of each projection 70 is a vertically curved surface 75, and at the base of each of the projections 71 is a vertically curved surface 76. In the present illustrative disclosure, each surface 75 is provided on a vertically adjustable member 77 which fits in a groove 78 in a die block 32 and which is adapted to be secured in adjusted position by a set screw 79. It is to be understood that the machine will be provided with die elements of various sizes and shapes which are interchangeable so that the machine may be employed for making clasps of the character described of almost any desired shape or size.

The operation of the machine is briefly as follows: The size and shape of the clasp to be made having been determined by an examination of the tooth to which it is to be applied, die members 20 and 30 of the required size and shape will be selected and secured in place. The holders 35 for the side die elements will then be transversely adjusted so as to bring the grooves 33 along side of the bottom die 30. Also these holders 35 will be adjusted by turning the nuts 50 so that side die elements will project the desired distances above the top of the bottom die 30. It may be that one leg *b* of the clasp is to be longer than the other one in which event one of the side die elements will be adjusted in a higher position than the other one. Also the forming members 77 may be adjusted to produce the desired shape of the arm without lengthening the legs *b*. The machine having been properly adjusted, a piece of wire of the selected gage is placed so that it extends through the slots 74 in which position a portion of the wire is between the male die 20 and the bottom die 30. Then the lever 16 is operated so as to move the plunger 13 downwardly, thus

bringing the male die against the wire and forcing it down into the female die so that the U-shaped portion of the clasp is formed, as shown in Fig. 4. The ends of the wire are then bent around the horizontally curved forming surfaces. For example, if a clasp of a larger size is desired, the ends of the wire are bent about the surfaces 72, as shown by dotted lines in Fig. 6. Also the ends of the wire are bent or drawn down against the bending surfaces 75, thus completing the operation except for cutting off the ends of the wire, which may be done by any suitable tool.

It will be observed that the clasp is formed in inverted position.

It will further be observed that by the use of a machine constructed in accordance with the present invention, a clasp of the nature described may be very quickly, accurately and economically formed.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a dental machine for forming clasps of the character described, a female die having a bottom die element with a transverse groove and a pair of side die elements with grooves at right angles to the groove in the bottom die element, the said side die elements being adjustable, a male die having a transverse groove and vertical grooves leading therefrom, the grooves in said male die being complementary to the grooves in the female die, and means for moving the male die into and out of the female die.

2. In a dental machine for forming clasps of the character described, a female die having a central die element and two side die elements, said die elements having a U-shaped groove, means for adjusting said side die elements with respect to the central die element, and a male die having a U-shaped groove complementary to the groove in the female die.

3. In a dental machine for forming clasps of the character described, a female die having a U-shaped groove, a male die having a U-shaped groove complementary to the groove of the female die, and forming surfaces about which the arms of the clasps are

adapted to be bent whereby a curved formation is imparted to the arms.

4. In a dental machine for forming clasps of the character described, a female die having a U-shaped groove, a male die having a complementary U-shaped groove, a transversely curved forming surface at each side of and at the top of the U-shaped groove in the female die, said surfaces being adapted to have the wire bent therearound and a vertically grooved surface at the base thereof.

5. In a dental machine for forming clasps of the character described, a female die having a central die element and side die elements, said die elements having grooves forming a U, a male die element having a groove complementary to the U groove of said female die, and a projection on each of said side die elements with an edge alined with the groove thereof, said projections having surfaces curved in a plane at right angles to the lengths of the grooves in said side die elements, each of said die elements also having at its top a vertically curved forming surface.

6. In a dental machine for forming clasps of the character described, a female die having a central die element and a pair of side die elements, said die elements having grooves which together form a U-shaped groove, and a male die element having a U-shaped groove complementary to the U-shaped groove of the female die, each of said side die elements having a pair of projections of different sizes with a slot therebetween in alignment with the groove in the side die element, the external surfaces of said projections being horizontally curved, the tops of said side die elements at the base of each of said horizontally curved surfaces being vertically curved.

7. In a dental machine for forming clasps of the character described, a female die having a central die element and a pair of side die elements, said die elements having grooves which form a U-shaped groove, a male die having a groove complementary to the groove of the female die, each of the side die elements having a projection one edge of which is in alignment with the edge of the groove in the side die element, said projections having surfaces curved in a plane to which the grooves of the side die elements are normal, said side die elements also having adjustable vertically curved surfaces leading from the groove in the side die elements.

8. In a dental machine for forming clasps of the character described, a female die having a bottom die element with a transverse groove and a pair of side die elements with vertical grooves, a male die having a transverse groove and vertical grooves, the grooves in said male die being complementary to the grooves in the female die, and a pair of curved surfaces forming a bending corner at

- the upper end of each groove of each side die element.
9. In a dental machine for forming clasps of the character described, a female die having a central die element and a pair of side die elements, said die elements having grooves which form a U-shaped groove, a male die having a groove complementary to the groove of the female die, each of said side die elements having at the end of the groove therein a slot and bending surfaces at each side of said slot, and means for reciprocating said male die.
10. In a dental machine for forming clasps of the character described, a frame, a rail carried thereby, a central die, a male die opposed to said central die, a slide on said rail to each side of said central die, a holder vertically adjustable on each of said slides, and a side die element carried by each of said holders.
11. In a dental machine for forming clasps of the character described, a frame, a transversely extending rail thereon, a center die having a groove, a pair of slides disposed to said sides of said center die and adjustably mounted on said rail, screws for clamping said slides in place, a post carried by each rail, a holder vertically adjustable on each post, nuts for adjusting said holders, said die elements carried by said holders, and a male die substantially as described.
12. In a dental machine for forming clasps, a female die having a pair of side die elements, a male die element adapted to move into position between said side die elements to form a U bend in the clasp, a transversely curved forming surface at the top of each side die element, and a vertically curved surface at the base thereof.
13. In a dental machine for forming clasps, a female die having a pair of spaced side die elements, a male die element adapted to move into position between said side die elements to form a U bend in the clasp, and a projection on each of said side die elements, said projections having surfaces curved in a plane at right angles to the lengths of the arms of the U bend, each of said side die elements also having at its top a vertically curved forming surface.
14. In a dental machine for forming clasps, a female die having a pair of side die elements, a male die element adapted to move into position between said side die elements to form a U bend in the clasp, each of said side die elements having a slot adapted to receive the wire from which the clasp is formed, each of said side die elements also having bending surfaces at each side of said slot, and means for reciprocating said male die.
15. In a dental machine for forming clasps, a frame, a transversely extending rail thereon, a central die, a pair of slides dis-
- posed on opposite sides of said central die and adjustably mounted on said rail, means for holding said slides in adjusted position, a holder vertically adjustable on each of said slides, means for adjusting said holders, die elements carried by said holders, and a male die.
